UNITED STATES PATENT OFFICE.

HENRY RIDLEY BURNETT AND DAN BREARLEY BREARLEY, OF BARROW-IN-FURNESS, ENGLAND, ASSIGNEES TO THE BABCOCK & WILCOX COMPANY, OF BAYONNE, NEW JERSEY, A CORPORATION OF NEW JERSEY.

WATER-GAUGE DEVICE FOR BOILERS.

Application filed March 12, 1924. Serial No. 698,773.

To all whom it may concern:

Be it known that we, HENRY RIDLEY BURNETT AND DAN BREARLEY BREARLEY, subjects of the King of Great Britain, residing at 5 237 Abbey Road, Barrow-in-Furness, England, and at 1 Wheatclose Road, Barrow-in-Furness, England, respectively, have invented certain new and useful Improvements 10 in Water-Gauge Devices for Boilers, of which the following is a specification.

Our invention relates to improvements in and connected with water gauge indicating and alarm devices for use in conjunction with steam boilers, and will be best understood from the following description taken 15 with the annexed drawings, in which Fig. 1 is a diagrammatic front elevation of an illustrative embodiment of our invention shown in conjunction with a high and low water 20 steam whistle alarm, the front of the containing case and indicating scale being removed; Fig. 2 is a section on the line X—Y of Fig. 1, and Fig. 3 a section on the line E—O of Fig. 1.

25 In the embodiment shown, a receptacle of cylindrical shape is connected with the steam space and with the water space of a boiler and is movable up or down with variation of its weight due to the variation of the 30 quantity of water therein.

Referring to the drawings, F denotes the receptacle closed at both ends and suspended on knife edges from links F', suspended from knife edges of a forked beam B, which 35 is supported on the knife edge fulcrum X which is fixed to the back of the containing case C. Near the upper and the lower ends of the receptacle are attached flexible U-tubes U, which are connected with the steam 40 and water spaces of the boiler respectively, and the limbs of which extend parallel with the sides of the case in a horizontal position and pass through the case, being securely clamped thereto.

45 The weight of the receptacle F is counterbalanced by an adjustable counterweight W attached to the beam B.

The beam B is connected by means of a link L to the pointer P, which is pivoted at 50 X'. The weight W is adjusted so that the beam B is horizontal when the receptacle F is half full of water and the length of the link L is so adjusted that under these conditions the pointer P is also in a horizontal

position, indicating that the water is at the 55 normal working level. Since the U-tubes U are connected to the steam and water spaces of the boiler, as the water rises in the boiler, it also rises in the receptacle F.

The increase in the weight of water in the 60 receptacle causes the receptacle to move downwards, movement being permitted due to the flexibility of the U-tubes. The downward movement of the receptacle causes the counterweight W to rise; the long arm of 65 the beam B connected by the link L to the pointer P also rises, the consequent rise of the pointer P indicating a rise in the water level. It will be seen that an important 70 advantage is had by the use of the U-shaped connections U, in that the expansion or contraction of the tubes, due to varying conditions of temperature in the tubes, is without effect on the indicator P or any control 75 arrangement used in connection with the device.

It will be obvious that, when the level of the water in the boiler falls, the reverse action takes place.

As it will be understood, the indicator can 80 be made to magnify the variations in the water level, as the extent of movement of the pointer P depends upon the relative 85 lengths of the lever arms. An opal glass or other scale (not shown) is fixed immediately behind the pointer P, the scale being preferably illuminated by an electric lamp fixed in the case. By this means small movements of the pointer are made clearly visible from a considerable distance.

It is desirable that the operation of the 90 alarm device not interfere with that of the water level indicator. In the arrangement shown I have provided a connection between the indicator and the alarm such that movement of the alarm device is unable to influence the position of the indicator. Such a connection I term "non-reactive." Referring to Figs. 1 and 2, the lever L', to which a weight W' is attached, is pivoted at X'. The 95 lower portion of this lever forms a cam C'. The distribution of the weight is such that the lever tends to fall or rotate about the pivot X', but is prevented under normal conditions from falling by a latch L² on the lever 100 L' slidably engaging a projecting bracket B² fixed to the beam B, the extent of overlap 105 of the latch L² and the bracket B² determin-

ing the permissible travel of the beam B without affecting the lever L'. If, however, the end of the long arm of the beam B rises above or falls below predetermined points due to rise or fall of water in the receptacle F, the latch L² disengages the bracket B³ and the lever L' being released, rotates about the pivot X², causing the cam C' to press the stem S of a steam whistle, whereby to blow the whistle until the lever L' is reset. By means of this arrangement, the operation of the alarm does not interfere with the indicator.

To minimize or prevent surging of the pointer, particularly in connection with marine work, there may be provided a stationary dash-pot casing Y, in which is movable a plunger Z, linked to an arm P' integral with or fixed to the pointer P.

It will be seen that expansion outwardly of anchored branches of the U-tubes will be compensated for by the expansion inwardly of the floating branches, so that the position of the receptacle F in space will be substantially unaffected by variation in the temperature of the U-tubes.

Instead of employing a steam whistle, the beam B may be arranged to close an electrical circuit, when the free end of the long arm rises above or falls below predetermined points and that the closing of this circuit can be utilized to ring a bell or perform other operations, such as the starting or stopping of feed pumps.

In conjunction with, or in line of, the audible indicator above described, there may be provided an electrically controlled indicator. For instance, there may be associated with the beam a series of stationary contacts of different lengths adapted to enter a mercury cup or the like suspended from the beam, each contact being associated with a particular circuit including a lamp, the mercury in the cup being common to all the circuits, so that, when the contacts successively dip into the mercury or emerge from the mercury as the water level in the reser-

voir rises or falls, successive electric lamps will be lit or extinguished.

We claim:

1. A water level indicating device, comprising in combination, a receptacle, conduits adapted to connect said receptacle with the steam and water spaces of a boiler and permitting movement of said receptacle in accordance with the weight of water therein, indicator actuating means comprising a lever connected to said receptacle, an alarm device, an alarm actuating means, and a non-reactive connection between said indicator actuating means and said alarm actuating means.

2. A water level indicating device, comprising in combination, a receptacle, conduits adapted to connect said receptacle with the steam and water spaces of a boiler and permitting movement of said receptacle in accordance with the weight of water therein, indicator actuating means comprising a lever connected to said receptacle, an alarm device, an alarm actuating means comprising a pivoted lever having a normal position in which its center of gravity is above its pivot, and means associated with said indicator actuating means for releasing said last-mentioned lever from said position upon extreme movement in either direction of said indicator actuating means.

3. A water level indicating device, comprising in combination, a receptacle, conduits adapted to connect said receptacle with the steam and water spaces of a boiler and permitting movement of said receptacle in accordance with the weight of water therein, indicator actuating means comprising a lever connected to said receptacle, an alarm device, an alarm actuating means, a connection between said indicator actuating means and said alarm actuating means, said connection being operative upon extreme movement of said indicator actuating means continuously to actuate said alarm until reset.

HENRY RIDLEY BURNETT.
DAN BREARLEY BREARLEY.
